[57] CLAIM

The ornamental design for a floppy disk holder, as shown and described.

DESCRIPTION

FIG. 1 is a perspective view of a floppy disk holder showing my new design;

FIG. 2 is a top plan view thereof;

FIG. 3 is a perspective view thereof looking from the right rear in FIG. 1;

FIG. 4 is a bottom plan view thereof;

FIG. 5 is a perspective view thereof looking in the same direction as in FIG. 1, but opened to a position for use; and

FIG. 6 is a top plan view thereof in the open position of FIG. 5.
